ABSTRACT

Automatic machine for spraying shoe components. Comprises a stationary spray gun and a rotary table carrying a support for a component to be sprayed. Support is moved linearly across the table and the table turned in pre-set sequence so that the edge of the component is sprayed all round.

FIG. 5

AUTOMATIC SPRAYING MACHINES

This invention relates to automatic spraying machines in which a component to be sprayed is moved past a stationary spraying device. The invention finds its primary, but not exclusive, use in the shoe industry in machines for applying dye or paint to the edges of sole units, platforms and foreparts.

According to the invention there is provided an automatic spraying machine, comprising a stationary spraying device, a table which is turnable with respect to said device, a support for a component to be sprayed, the support being carried by the table for movement in a linear path across the same, and drive means for the table and for the support, whereby, in use, a component to be sprayed can be moved past the spraying device linearly by movement of the support and in an arcuate path by turning the table.

In use, a component to be sprayed is placed on the support and the machine operated to move the component in the required path. It will be appreciated that by effecting linear and arcuate movement of the component in appropriate sequence or simultaneously, the machine can be adapted to spray a wide range of different-shaped components. Moreover, the surface of the component being sprayed is maintained at a constant distance from the spraying device, which makes for uniformity of spraying.

When spraying the edges of a shoe component for example (to which reference will hereinafter be confined for convenience) the component will be positioned edge-on to the path of spray from the spraying device. Starting, say, with one side edge, the support will be initially traversed across the table so that the device sprays that edge. Next, by turning the table through a half revolution, an end edge of the unit is sprayed. Another traverse of the support directs the other side edge towards the spray and a final further half revolution of the table causes the other end edge to be sprayed. A second spraying device may be brought into operation to spray the tread surface of the sole unit during one of the traverses of the support across the table. It will be appreciated that, by suitably modifying the sequence, platforms, foreparts etc., can also be sprayed.

Preferably the support is carried by a rod which projects upwardly through a diametral slot in the table and is connected, below the latter, to a piston and cylinder unit carried by the table and arranged to traverse the rod along the slot and so effect linear movement of the support.

The stroke of the piston and cylinder unit may be controlled by a cam which moves with said support and a switch which is operated by the cam, the position of the switch being adjustable to vary the stroke of the piston and cylinder unit and hence the extent of the linear movement of the support. In this way, the machine can be adjusted for spraying components of different lengths.

Provision is preferably also made to adjust the speed of movement of the support so that the time for which a particular part of a component is sprayed can be varied. The speed of turning of the table may also be adjustable for the same reason.

To facilitate understanding of the invention and enable it to be readily carried into practice, reference will now be made to the accompanying drawings which il-

lustrate one embodiment thereof, by way of example, and in which:

FIG. 1 is a front view of a sole unit spraying machine in accordance with this embodiment,

5 FIG. 2 is a plan view corresponding to FIG. 1,

FIG. 3 is a sectional view on line III — III of FIG. 2, looking from the rear of the machine,

FIG. 4 is a vertical sectional view on line IV — IV of FIG. 3, and,

10 FIG. 5 is a diagram of the pneumatic circuit of the machine.

Referring first to FIGS. 1 and 2 the machine basically comprises a floor-standing casing 1 presenting a flat upper surface on which is mounted a rotatable circular

15 table 2 adapted to carry a sole unit to be sprayed (as will be described). Mounted on the front side of the casing 1 is a frame 3 carrying a spray gun 4 of conventional form, the frame being adjustable both heightwise and laterally to vary the position of the spray gun 4.

20 Table 2 is formed with a diametral slot 5 through which projects a rod 6 connected by a screwthreaded coupling to a further co-axial rod 7 carrying at its upper end a support 8 for a sole unit (designated S). The support comprises a pair of slotted slides 9 which are dis-

25 posed with their side faces in sliding contact and are adapted to be locked in an adjusted position relative to one another by a pair of bolts 10 provided with wing nuts. This enables the length of the support to be adjusted to accommodate different-sized sole units. Each

30 slide 9 has a pair of upstanding pins 11 which engage and locate the face of the sole unit remote from its tread surface. A drip tray 12 is provided at the bottom of rod 7 to collect excess paint falling from the sole unit S in use.

35 To prevent paint, (or other foreign material) falling through the slot 5 in table 2, the slot is sealed by two spring steel strips 13 (see FIG. 3), received in guideways along the sides of slot 5. Each strip is connected at one end to the rod 7 and at its opposite end is received in a housing 14 on the table, being arranged in a coiled configuration in the latter. In operation, rod 7 moves along slot 5 as will be described, the strips 13 respectively coiling up into uncoiling from their housings 14 as the rod moves.

40 45 Reference will now be made more specifically to FIGS. 3 to 5 in describing the driving mechanism of the machine.

The mechanism is designed to initially move the sole unit support 8 from left to right (FIGS. 1 and 2) along the slot 5 in table 2, starting from the position shown, whereby one side edge of the sole unit S will be sprayed. On completion of this movement the mechanism rotates table 2 through half a revolution in the anti-clockwise direction so that the spray gun applies

50 paint to the heel edge of the unit; this brings the carrier 8 back to the starting position with the sole unit facing in the opposite direction. Next the carrier is again moved from left to right along the slot in table 2 so that the other side edge of the unit is sprayed. Finally, the table performs a further half a revolution in the anti-clockwise direction so that the toe edge of the unit is sprayed, the latter coming to rest in the position from which it started. This completes the cycle of operation

55 60 65 and the sole unit is removed from its carrier and replaced by a fresh unit.

In the described embodiment, a single spray gun only is used to spray the side edges of the unit, although pro-

vision is made in the machine for a second spray gun to be mounted on the lefthand end of the casing 1 to spray along the line of slot 5 and apply paint to the tread surface of the unit.

Two pairs of snap connectors 15a, 15b are provided in the front of casing 1, each spray gun being plugged into one pair; only the pair 15a are being used in the illustrated embodiment.

The part of the mechanism for moving the rod 6 (and hence the sole unit carrier 8) along slot 5 is illustrated in FIG. 3 and comprises a so-called "Tol-o-matic" cable cylinder 16 mounted on the underside of table 2. Cylinder 16 is an air cylinder having mounted therein a piston 17 connected to a pair of cables 18. Each cable extends axially of the cylinder, travelling around a pulley 19 disposed adjacent the relevant end of the latter and is connected to rod 6 by way of a bracket 20. It will be appreciated that by applying air alternately to opposite ends of cylinder 16 the piston is caused to reciprocate in the cylinder, carrying with it the rod 6. Rod 6 is guided during this movement on a rod 21 mounted parallel to cylinder 16. Shaft 21 is hollow and perforated, the exhaust air (which contains oil droplets) from the pneumatic circuit of the machine being delivered into the shaft as can be seen at its lefthand end in FIG. 3 for lubrication purposes.

Application of air pressure alternately to opposite ends of cylinder 16 is controlled by valves in the pneumatic circuit of the machine as will be described.

The stroke of the piston 17 in cylinder 16 is controlled by a valve V¹ which is visible in FIG. 3, being actuated by a cam 22 mounted on the lower end of rod 6. Valve V¹ is mounted on a screwed spindle 23 and is slideable on a fixed guide rod 24. Spindle 23 carries a knurled knob 25 at its outer end (see also FIGS. 1 and 2), turning of which moves the valve V¹ parallel to the axis of cylinder 16 when in its rest position so as to vary the position in which the valve is operated. A pointer 26 cooperating with a fixed scale 27 is provided at the front of the casing of the machine (FIG. 1) to indicate the chosen stroke length.

As can be seen from FIG. 2 the "Tol-o-matic" cylinder 16 is mounted on the underside of table 2 so as to turn with the latter; in fact the cylinder assembly carries the table. Thus, a bearing block 28 is secured to the bottom of cylinder 16 and mounted on a shaft 29 fixed in bearings 29a.

To permit the delivery of air to cylinder 16, pipework 30 connected to respectively opposite ends of the cylinder is also connected to bearing block 28 and, via bores in the latter, to a rotary coupling assembly 31 to which further, stationary pipework (not shown) is connected. The coupling is designed to allow transmission of air from the stationary pipework to the pipework 30 which rotates with the cylinder 16.

Rotary movement of the table 2 is effected by means of a gear wheel 32 connected to shaft 29. This gear wheel is driven by an air motor 33 having a driving pinion 34 in mesh with its own teeth. The speed of air motor 33 (and hence the speed at which the table turns), is controlled by a second screwed spindle 35 having a knurled knob 36 (visible in FIG. 1) which operates a conventional flow regulator valve 37 (FIG. 4) in the supply to the motor.

Gear wheel 32 also functions as a sequence controller for the pneumatic circuit of the machine. Thus, as can be seen more particularly in FIG. 4, a number of

cams 38 are mounted on the upper surface of gear wheel 32 to control valves V², V³, V⁴ in the pneumatic circuit.

Valve V⁴ is fixed as can be seen, but valves V² and V³ are carried by a bracket 39 which is pivoted at 40. The position of bracket 39 is controlled from the air motor speed control shaft 35 by way of a sleeve 41 on that shaft connected by a linkage 42 to bracket 39. The purpose of this arrangement is to automatically adjust the positions of the valves V² and V³ in accordance with the motor speed in order to take account of the inertia of the system.

Referring finally to FIG. 5, this view shows diagrammatically the "Tol-o-matic" cylinder 16, the gear wheel 32 and its driving air motor 33 and spray gun 1. A second spray gun is indicated in chain lines for connection to the circuit by way of the associated pair of snap connectors 15b. A four-position rotary switch 43 is provided to control the spray guns as will be explained. Incorporated in the circuit are the valves V¹, V², V³ and V⁴ referred to previously and a foot treadle-operated main control valve V⁵. The air supply to the circuit is along line SL.

In addition the circuit includes a number of air valves V⁶ to V¹³, (some of which are spring return and some air operated as shown), and the two non-return valves NRV.

The operation of the circuit is as follows:

Operation of valve V⁵ has two effects. Firstly it delivers air to the spray gun 1 by way of valve V⁶ along line L¹. Secondly, by way of valves V⁷ and V⁴, a valve V⁸ associated with one end of the "Tol-o-matic" cylinder is operated. A second similar valve V⁹ is associated with the other end of cylinder 16.

It should at this stage be noted that the construction of the rotary coupling 31 (visible in FIG. 3) is such that air delivered to cylinder 16 through valve V⁹ always passes to the end of the cylinder which is shown at the left in FIG. 5 and air delivered by way of valve V⁸ always goes to the end of the cylinder shown at the right.

Operation of V⁸ therefore connects the righthand end of cylinder 16 to exhaust by way of a valve EV. This releases the piston 17 of cylinder 16 for movement to the right under the action of the constant air pressure delivered along line L² from the supply SL to the lefthand end of cylinder 16 via valve V⁹. This moves piston 17 to the right until the cam 22 carried thereby operates valve V¹. The exhaust valve EV is adjustable, being controlled by a knob 44 (FIG. 1), to enable the speed of movement of piston 17 to be controlled.

Valve V¹, which is connected to supply line SL, then delivers air to a valve V¹⁰, which is connected to supply line SL, then delivers air to a valve V¹⁰, whereby the air motor 33 receives air from a separate air supply line SL2 by way of speed control valve 37. This drives gear wheel 32 in the anti-clockwise direction to turn the table 2. Simultaneously, valve V⁷ is operated to cut off the air supply to cylinder 16.

Gear wheel 32 continues to rotate until cams 38a, 38b and 38c operate the valves V⁴, V³ and V² respectively. Operation of valve V² connects the air supply line SL to valve V¹⁰ to return this valve to its original position and switch off the air supply to the motor. Valve V³ returns valve V⁷ to the position in which it is shown so that air is delivered to valve V⁴. As the cam 38a has operated valve V⁴, it will at this time be in its righthand position and therefore deliver the air from V⁷

to valve V⁹. This operates valve V⁹ to connect it to the exhaust valve EV and allow the air pressure acting on valve V⁸ to move the piston 17.

It will be remembered that cylinder 16 has been turned end for end by rotation of gear wheel 32 so that piston 17 is back to the position in which it is shown in FIG. 5. Valve V⁸ is connected to the end of cylinder 16 which is now at the lefthand side by virtue of the construction of coupling 31. Operation of valve V⁹ will therefore connect to exhaust the end of cylinder 16 which is at the righthand side and piston 17 will move from left to right. When piston 17 reaches the end of its travel, valve V¹ will be operated and the 180° rotation of gear wheel 32 (and hence table 2) will follow as described previously.

At the end of this movement of gear wheel 32, valves V³ and V² will again be operated by the further cams 38d and 38e respectively. V² switches off the air motor 33 as previously and V³ delivers air to V⁴. Cam 38a is at this time back in the starting position in which it is shown so valve V⁴ adopts its left-biased position. Air is therefore delivered by V⁴ along line L3 to switch off the foot treadle-operated valve V⁵ and terminate the cycle.

The cams 38b and 38e are arranged so that valve V³ is always operated slightly before V². This has two effects. Firstly, it ensures that the air pulse to operate air cylinder 16 begins before the air motor is switched off, so that there is no pause in the movement of the sole unit support 8 at the end of the first half revolution of table 2, which would cause excess paint to be applied to the unit. Secondly the spray gun 1 is switched off slightly before the air motor at the end of the machine cycle, again to ensure that no excess paint is applied.

It will be noted that valve V⁶ referred to above is a manually operable valve by which the spray gun 1 can be operated without activating the remainder of the circuit. Its operating button is indicated at 45 in FIG. 1.

The circuit also includes a push-button operated reset valve V¹¹ (the operating button being denoted 46 in FIG. 1) which is operated in the event that table 2 is turned out of position for any reason. Operation of valve V¹¹ connects supply line SL to valve V¹⁰, which operates the air motor 33 and causes the cycle of operation of the machine to be automatically completed.

Rotary switch 43 is associated with two further valves V¹², V¹³ for controlling the second spray gun. The arrangement is such that, in normal operation with spray gun 1 only in use, the switch will be set in position 1 or 3. If the switch is set to position 2, the second gun will spray until the end of the second operation of air cylinder 16. Thus, where a shoe platform or forepart is being sprayed, the gun will spray both side edges of the component and the toe edge.

With the switch in position 4, the gun will spray only during the first actuation of air cylinder 16. This setting is intended for use with the second spray gun positioned at the lefthand end of the machine casing (FIG. 1) in line with the slot in table 2 for the purpose of spraying the tread surface of a sole unit on carrier 8. I claim:

1. An automatic spraying machine comprising: a stationary spraying device; a table which is turnable with respect to said device; a support for a component to be sprayed, the support being carried by a rod which projects upwardly through a diametral slot in the table, and is connected, below the latter, to a piston and cylinder unit carried by the table and arranged to traverse the rod along the slot for movement of the support in a linear path across the table; and drive means for the table and for the support, whereby, in use, a component to be sprayed can be moved past the spraying device linearly by movement of the support and in an arcuate path by turning the table.

2. A machine according to claim 1, wherein the stroke of the piston and cylinder unit is controlled by a cam which moves with said support and a switch which is operated by the cam, the position of the switch being adjustable to vary the stroke of the piston and cylinder unit and hence the extent of the linear movement of the support.

3. A machine according to claim 1, wherein means are provided to vary the speed of operation of the piston and cylinder unit in accordance with the required speed of movement of the support across the table.

4. A machine according to claim 1, wherein the slot in the table is sealed by means of a pair of spring steel sealing strips each connected at one end to the rod and at its opposite end being coiled in a housing adjacent the end of the slot, whereby each strip either uncoils from or coils into its housing as the rod moves along the slot.

5. A machine according to claim 1, wherein the support comprises a pair of slide members which can be adjusted with respect to one another to vary the size of the support to cater for different size components to be sprayed.

6. A machine according to claim 1, wherein the rod carries a drip tray mounted below the support to receive excess paint or the like falling from a component on the support.

7. A machine according to claim 1, wherein the table is carried by a rotary shaft and wherein the drive means for the table comprises a gear wheel mounted on said shaft, and a motor having a driven pinion arranged in mesh with the gear wheel, the arcuate extent to which the table turns being determined by cams mounted on said gear wheel and associated stationary switches connected in the power supply to the motor.

8. A machine according to claim 7, wherein the table is carried by said rotary shaft through the intermediary of the piston and cylinder unit, the shaft being connected to the latter by way of a rotary fluid coupling arranged to permit the supply of operating fluid to the piston and cylinder unit as the table turns.

9. A machine according to claim 7, wherein operation of the piston and cylinder unit is also controlled by cams on the gear wheel, whereby both the linear and arcuate movements of the support are determined by the positions of the cams in automatic sequence.

* * * * *
